UNITED STATES PATENT OFFICE.

JOHN WATTMANN, OF BERLIN, LANKWITZ, GERMANY.

METHOD OF TRANSPORTING RAILS OF RELATIVELY GREAT LENGTH.

Application filed May 28, 1927, Serial No. 195,081, and in Germany June 3, 1926.

The invention relates to a novel method of transporting railway rails and the like of excessive lengths to the site of application of such rails, as, for example, in tunnels, on viaducts, raised railroad beds and similar locations, where it is difficult or practically impossible to unite successive standard lengths of rails by electric welding or similar mode of jointure. To this end, the invention comprises the mounting of rails of relatively great lengths, as, for instance, one thousand feet, upon separate cars spaced at intervals, securing the rails against lateral movement and preferably against longitudinal movement with respect to the individual cars, and moving the cars to the site where the rails are to be applied.

The invention is especially applicable in the practice of electrically welding railway rails, where it is difficult or impossible to effect the weld of the rail in situ, which is usually the case when the rails are laid in tunnels, on viaducts, raised road beds or the like, the present method admitting of the rails being welded together to form continuous lengths up to and including one thousand feet at some point remote from the site of application of the rails, and preferably in a factory or plant equipped to effect alumino-thermic welding or an equivalent jointure of rails and the like, and transporting these relatively great lengths of welded rails to the place where the latter are to be applied in position.

One mode of applying the invention is illustrated in the accompanying drawings, in which:—

Fig. 1 is a plan view of a curved section of railroad track with three cars thereon and a relatively great length of rail carried by the cars.

Fig. 2 is an end elevation thereof.

Fig. 3 is a fragmentary side elevation.

Referring to the drawings, *a* indicate the rails of a railway track and *b* a rail of relatively great length, which is to be transported over the railway track. Disposed on the railway track at spaced intervals is a series of railway cars or trucks, each preferably comprising two pairs of longitudinal sills *c*, *c* connected by transverse beams *d*, *d* to constitute a rigid framework. The car wheels are mounted upon short axles supported in journal bearings attached to the under sides of the longitudinal members *c*, *c*. Connected to

each of the transverse beams and pendent in the space between the side frames or sills *c* are brackets *e*, which are preferably recessed to receive the length of rail to be transported and to which said rail is rigidly secured against lateral movement, and preferably also against longitudinal movement by any suitable means, as, for example, a common form of clamp comprising arms *f*, *f* pivoted intermediate their length, at *g*, between the brackets *e*, *e*, the lower end of the arms engaging the rail and the upper ends of the arms being actuated by a double screw *h*. As indicated in the drawings, at least three separate cars are required to transport rails of the relatively great length indicated and, obviously, a large number of cars may be used where necessity or desirability therefor is apparent. By this particular arrangement of cars and suspension means for the rail to be transported, it will be seen that the series of cars and the rail mounted thereon and secured thereto against lateral movement and also against longitudinal movement, constitute a flexible vehicle, which will readily follow the curvature of the railroad track, as the cars are moved over the same, due to the inherent resiliency of the rail being carried. The latter will bend readily to conform to the curvature of the track over which it is being transported and will immediately resume its normal straight shape, when the transporting cars enter upon a straight stretch of track. Furthermore, the rail being transported constitutes the coupling between the several cars, so that the supporting cars and the long rail carried thereby may be readily moved over the track as a flexible unit capable of adapting itself to various changes in the direction of the track. It has been successfully demonstrated that rails of the relatively great length indicated may be successfully and economically transported without impairing the rail and without imposing undue lateral stresses on the cars or the track-way sufficient to impair either.

Instead of suspending the rail to be transported beneath the series of cars carrying the same and between the wheels, which arrangement was designed to reduce the chances of upsetting any of the cars by the lateral thrust of the supported rail upon encountering a curve, it has also been found entirely feasible to secure one or more lengths of rails of the order indicated upon ordinary flat cars,

- the cars being spaced at intervals on the track and the rails being secured to the floors of the flat cars against lateral and longitudinal movement, so that the rail or rails serve as 5 couplings between the cars and also, because of the rigid connection between the same and the cars, said rails follow the contour of the track over which the cars operate, by reason of the flexibility and elasticity of the rails.
- 10 The invention not only involves utility in facilitating the welding of the rails at locations especially equipped for this purpose, but involves elements of material economy in that it avoids the expense of transporting 15 and maintaining the welders at the site where the rails are to be applied.

What I claim is:

1. The method of transporting rails of relatively great length, which comprises mounting the same on at least three separate railway cars, securing the rails to the cars against lateral movement, and moving the cars to the site where the rails are to be applied. 20
2. The method of transporting rails of relatively great length, which comprises mounting the same on at least three separate railway cars, securing the rails to the cars against lateral and longitudinal movement relative to said cars, and moving the cars to the site where the rails are to be applied. 25

In testimony whereof I affix my signature. 30

JOHN WATTMANN.
